FIG. 9

UNITED STATES PATENT OFFICE.

FLORENCE C. BIGGERT, JR., OF CRAFTON, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

CLIPPING-SHEARS.

1,203,842.

Specification of Letters Patent.

Patented Nov. 7, 1916.

Application filed November 30, 1914. Serial No. 874,742.

To all whom it may concern:

Be it known that I, FLORENCE C. BIGGERT, Jr., a citizen of the United States, and resident of Crafton, in the county of Allegheny and State of Pennsylvania, have invented a new and useful Improvement in Clipping-Shears; and I do hereby declare the following to be a full, clear, and exact description thereof.

- 10 My invention relates to clipping-shears. In the manufacture of butt-weld tubing, the skelp is drawn through the welding-bell so as to bring the edges into contact for welding. In order that the front end of the skelp to which the tongs are attached may enter the welding-bell readily, it is customary to clip off the end of the skelp so as to have the end portion in the shape of a truncated cone.
- 20 My invention has reference to a clipping-shear for clipping the ends of the skelp in this manner, where a long strip of skelp is cut into proper lengths, and at the same time clipped in the above manner by a continuous process, and thereby reducing the waste due to crop-ends, at the same time greatly reducing the labor in the handling of the skelp.
- 30 To these ends my invention consists, generally stated, in upper and lower knives so shaped as to cut the metal diagonally, an auxiliary lower knife adapted to coöperate with the upper knife to make the cross-cut, whereby triangular pieces are cut from both sides of the skelp, and finally, an auxiliary upper knife which coöperates with the lower stationary knife to make the final cross-cut to sever the skelp-blank from the main section.
- 40 In the accompanying drawings, Figure 1 is a front view of my improved shears, shown in duplicate; Fig. 2 is a side view with the pinch-rolls in section; Fig. 3 is an enlarged sectional detail of the knives; Fig. 4 is an enlarged sectional detail, showing the upper and lower knives in cutting position, and the lower auxiliary knife up in position for cutting; Fig. 5 is a sectional view of a portion of the end of the skelp; Fig. 6 is a plan view before the final cut has been made; Fig. 7 is an enlarged sectional detail showing the manner in which the skelp is curved to bend slightly; Fig. 8 is an inverted plan view of the top knife; Fig. 9

is a plan view of the bottom knife, and Fig. 55 10 is a plan view of a portion of the skelp showing the clipped end.

As stated above, my improved shears are shown in duplicate, but in describing the same, the parts will be referred to in the singular number.

The numeral 2 designates a suitable frame which has the bracket 3 for the support of the motor 4. The motor-shaft has the pinion 5 which meshes with the gear-wheel 6 65 on the shaft 7, and said shaft has the pinion 8 which meshes with the large gear-wheel 9. This gear-wheel 9 is mounted rigidly on the shaft 10. A clutch-member 11 is rigidly mounted at one end of the shaft 10, and said 70 clutch-member is adapted to be thrown into engagement with the clutch-member 12, loosely mounted on the shaft 10. This clutch-member 12 forms part of a sleeve 13 which carries the eccentrics 14 and 15, said 75 eccentrics being inclosed within the eccentric-straps 16 and 17, respectively. The eccentric-rod 18 is connected up to the upper knife-block 19 which carries the upper-knife 21, provided with the diagonal cutting edges 80 22, and the cross-cutting edges 23. The upper knife also carries the auxiliary cross-cutting knife 24, whose cutting edge 25 is slightly above the cutting edges 22 and 23 of the upper knife.

The lower knife-block 26 carries the lower-knife 27 with the diagonal cutting edges 28, with which the diagonal cutting edges 22 of the upper knife coöperate. This lower-knife 27 is stationary, and a former 90 or shaper 29 which is secured to the knife-block 26 by a bolt 30, projects over and rests upon the upper face of the knife 27. The edges of the former 29 are rounded as at 31 so that the clipped end of the skelp is 95 slightly rounded as at 33 by the clipping operation, as indicated in Figs. 5 and 7.

The lower auxiliary cross-cutting knife 34 is supported in the block 35 which moves in suitable guides 36 and the lower end of 100 said block is connected to the arm 37 of the toggle 38, the lower arm 39 of the toggle being connected to the crank-arm 40 on the shaft 41. A rod 42 is connected to the crank-arm 40 and said rod is connected to 105 the eccentric-strap 17 of the eccentric 15.

The long length of skelp 43 to be cut is fed to the shears between the pinch-rolls 45.

These pinch-rolls are driven by a train of gearing 46, connected up with the large gear-wheel 9.

In the operation of the machine, the skelp 43 is advanced into position between the knives and the operators throw the clutch 11 into engagement with the clutch 12, whereupon the eccentrics 14 and 15 are rotated, and the eccentrics are so arranged with 10 reference to each other that the eccentric 14 which controls the movement of the upper knife, first lowers said upper knife 21, bringing its diagonal cutting edges 22 into engagement with the skelp and the further 15 downward movement of the upper knife cuts the skelp diagonally, the cutting edges 22 of the upper knife coöperating with the cutting edges 28 of the lower knife, and as said upper knife descends, it also acts in 20 connection with the former 29 to slightly bend the edges of the skelp, as clearly indicated in Fig. 7. The eccentric 15 is so timed to raise the lower auxiliary knife 34 just as the upper knife is completing the diagonal 25 cut as indicated in Fig. 4, and said auxiliary knife 34 is raised by the toggle 38 up into the position indicated in Fig. 4, so as to have its cross-cutting edge coöperate with the cross-cutting edges 23 of the upper 30 knife, whereby the cross cut is made partially at each side of the skelp, so as to cut out a triangular portion at each side, as indicated in Fig. 6. When this has been accomplished, the lower auxiliary knife 34 is 35 withdrawn as indicated in Fig. 3, and the upper auxiliary knife 24 by the further descent of the upper knife, acts to complete the cross-cut, its cross-cutting edge 25 coöperating with the cross-cutting edge 28a of 40 the lower knife 27. When this cut has been completed, the upper knife is withdrawn and the skelp-blank which has been clipped is fed forward by the pinch-rolls 45 and the skelp 43 is advanced for another cutting operation. In this manner I provide for the 45 diagonal clipping of the skelp, and the cross-cutting so as to give skelp-blanks with straight ends, while at the same time the clipped portion of the skelp is turned upward to facilitate its entrance into the welding-bell.

What I claim is:

1. In shears, the combination of an upper knife and a lower knife having diagonal 50 and cross-cutting edges, means for raising and lowering the upper knife, an auxiliary lower cross-cutting knife coöperating with

the cross-cutting edge of said upper knife, means for raising and lowering said auxiliary cross-cutting knife, and an auxiliary cross-cutting knife on said upper-knife co-operating with the cross-cutting edge of the lower knife. 60

2. In shears, the combination of upper and lower knives having diagonal-cutting edges and cross-cutting edges, means for raising and lowering the upper knife, a lower auxiliary cross-cutting knife, means for raising said auxiliary cross-cutting knife when the upper knife has completed its diagonal cut, whereby the lower auxiliary cross-cutting knife coöperates with the cross-cutting edge of the upper knife, means for lowering said lower auxiliary cross-cutting knife after the completion of the cut, and an upper auxiliary cross-cutting knife with its cutting edge above the cutting edges of said upper knife, and coöperating with the cross-cutting edge of the lower knife to complete the cross-cut. 70

3. In shears, the combination of an upper and lower knife having diagonal cutting edges and cross-cutting edges, a former on the lower knife, the upper knife having a recess conforming with the shape of said former, and knives coöperating with the cross-cutting edges of said upper and lower knives, whereby the cross-cut is made completely across the skelp or other object. 80

4. In shears, the combination of upper and lower knives having diagonal cutting edges and straight cross-cutting edges, and auxiliary cross-cutting knives coöperating with said upper and lower knives, whereby the cross cut is made completely across the skelp. 90

5. In shears, the combination of upper and lower knives, having diagonal and cross-cutting edges, an eccentric, connections between said eccentric and the upper knife, the lower auxiliary knife having a cross-cutting edge coöperating with the cross-cutting edge of the upper knife, an eccentric, connections between said eccentric and said auxiliary knife, and an upper auxiliary knife having a cross-cutting edge coöperating with the cross-cutting edge of the lower knife. 100

In testimony whereof I, the said FLORENCE C. BIGGERT, Jr., have hereunto set my hand. 110
FLORENCE C. BIGGERT, Jr.

Witnesses:

EDWARD JONES,
ARNOLD P. BARK.
